UNITED STATES PATENT OFFICE.

HARRY VISSERING, OF KENTWORTH, ILLINOIS, ASSIGNOR TO THE OKADEE COMPANY, OF CHICAGO, ILLINOIS, A CORPORATION OF ILLINOIS.

LOCOMOTIVE-FRONT-END SUPPORT.

Application filed July 16, 1924. Serial No. 726,334.

This invention relates generally to closure supports, and particularly to a support for the type of closure used in boilers of railway locomotives, and commonly termed the 5 front end, as it is the plate for forming the forward end of the boiler.

This closure plate for the front end of a boiler is large and extremely heavy, and according to approved railway practice, is secured 10 to the boiler front end by a great number of stud bolts and nuts circumferentially arranged adjacent the outer edge of the front end plate. To make the joint between the boiler front and front end plate 15 absolutely tight against leakage, the nuts are turned down as closely as possible. When it is desired to remove the front end plate to reach the inside of the boiler shell, the nuts are all removed and the front end plate 20 moved away from the boiler shell. To loosen this front end plate and move it away from the boiler shell is rendered extremely difficult, as there is a tendency for the front end plates to stick, due to the rusting of the 25 parts and the action of the elements, aside from the factor of its great weight.

Still another difficulty encountered in the removal of the front end plate, is that its weight is such, the more so when auxiliary 30 apparatus is supported thereby, that a crane and tackle, or the like, is found necessary to carry the weight of the parts as soon as they are moved away from their positions of support by the boiler. This necessitates that 35 the engine be moved to a spot where such crane and tackle are at hand.

Again, in the development of modern railway practice it has been found necessary, owing to the increased size of the boilers 40 and the cylinders, and the limitations on the size of locomotive structures imposed by station platforms, tunnels, bridges, and other structures adjacent to the right of way, to mount certain structures, which it has heretofore 45 been possible to support at the side of the locomotive, on the front of the locomotive and most conveniently to support them on such front end, such structures being, for example, certain air cylinders and 50 compressor pumps. These structures being carried on the front end add further complications and difficulties and render access to the inside of the boiler shell even more inconvenient and expensive.

55 Furthermore, when an attachment in the

form of a hinge structure has been used by me for the support of the front end, and such supernumerary structures as the cylinders and pumps referred to are applied to such front end, such arrangement has been 60 found objectionable inasmuch as a great deal of weight is carried at a distance from the pivotal axis of the hinge structure, and upon removal of the nuts and the front end structure from the stud bolts, there has been 65 marked canting and consequent binding of the front end, owing to the increased tendency thereof to swing downward about the lower hinge structure as an axis.

The principal objects of this invention, 70 therefore, are to provide an improved arrangement whereby the front end plate and any associated parts can be moved away from the boiler front without the present expenditures required under existing practice; 75 the provision of an improved mounting between the front end plate and boiler plate now in use generally, which will permit of the employment of a pivoted connection between such front end plate and boiler front 80 without intolerable interference therewith by structures carried by the locomotive at the front of such front end plate and which will still permit the employment of such additional structures in their desired relationships; the provision of an improved construction by which such supplemental structures may be moved laterally away from the boiler front without at the same time detaching therefrom; the provision of an improved construction whereby such supplemental structures may be moved away from the boiler front and the front end plate without at the same time detaching them 85 from the boiler front; the provision of an improved construction whereby all the several structures mounted at the boiler front may be moved from their position of support thereby without detachment therefrom; the provision of a novel arrangement which 90 permits the several structures carried at the front of the boiler to be swung aside relatively to the boiler front so as to permit free access to the boiler interior without at the same time withdrawing them from their positions of support by the boiler; the provision of improved means whereby this may be accomplished without at the same time detaching them from the boiler; the provision 95 of improved means whereby the several 100 structures carried at the front of the boiler may be moved laterally away from the boiler front without at the same time detaching them from the boiler; the provision of improved means whereby the several 105 structures carried at the front of the boiler may be moved laterally away from the boiler front without at the same time detaching them from the boiler; the provision 110 of improved means whereby the several

elements referred to may be secured to the boiler front by an improved arrangement of stud bolts and nuts circumferentially arranged adjacent to the outer edge of the front end plate, characterized by the fact that such removal may be readily accomplished, and further characterized by the fact that the front end plate may be swung laterally to permit access to the boiler front without straining such supporting means; the provision of an improved arrangement of supporting means whereby elements carried at the front of a boiler may be securely detachably supported thereby; together with such further additional objects as may hereinafter be pointed out or appear as this description proceeds.

In attaining the objects referred to and in gaining certain additional benefits and advantages to be below disclosed, I have embodied certain constructions embodying my present invention, which are illustrated in the accompanying drawing, wherein:

Figure 1 is a front elevational view of a locomotive front embodying one exemplification of my present invention, wherein the closure is shown in closed position and certain associated parts are projected forwardly;

Figure 2 is a side elevational view of the structure of Figure 1;

Figure 3 is a plan view of the structure of Figures 1 and 2, a position assumed by certain of the elements upon movement from the position shown in full lines being indicated in dotted lines;

Figure 4 is a front elevational view of the locomotive front embodying another exemplification of my present improvements, where the closure is shown in closed position and certain associated parts are carried in parallelism with the front end;

Figure 5 is a side elevational view of the structure of Figure 4;

Figure 6 is a plan view of the structure shown in Figures 4 and 5; and

Figure 7 is a plan view showing the position assumed by certain parts illustrated in Figure 6, when they are moved from the position shown in such figure.

As will be observed on viewing the drawings, the boiler shell 10 and the front end closure plate 11 are held rigidly and tightly together in service condition by means of a row of bolts and nuts 12. This row is generally circular but when it is desired to support some element such as an air cylinder thereon, which element is not conveniently removable therefrom, a longitudinally split plate and a supplemental line of bolts may be employed as indicated at 12^a.

As these parts are all exposed to the elements, the front end plate will tend to stick to the stud bolts and the boiler front, and it is extremely difficult to pry the front end

plate loose from the boiler plate and handle it without elaborate tackle.

Furthermore, when it is pried loose special provision must be made to support the end of the front plate and move it away from the boiler opening so as to reach the boiler interior.

This is more marked when heavy structures such as the compressor pumps A and A' are supported by the front end plate. Such a structure as the pump A does not offer so much difficulty as does the pump A' inasmuch as the pump A is located closely adjacent to the axis of the hinge structures, but the pump A' is found in practice to place an almost intolerable burden upon the hinge structures inasmuch as the pump A' is not only of great weight per se but is also located at a relatively great distance from the hinge structures and consequently exercises a very marked torque upon them.

Referring now more particularly to the embodiment of the invention illustrated in Figures 1 to 3, it will be observed that in the structure here shown the boiler front 10 has associated therewith two sets of hinge structures, indicated generally at B, B', disposed on the opposite sides of the boiler.

These structures B, B' serve to support the pumps A, A' and in the present embodiment of the invention such support is attained by the employment of forwardly projecting bracket portions C, C', formed on the hinge structures B, B'.

The hinge structure B serves not only to support the pump A but also to support the front end closure 11 when the latter is moved from its supports by the row of stud bolts 12, the hinge and the closure being detachably connected by the several bolts and nuts indicated at 12^b.

The hinge structure B as will presently appear is adapted not only to permit pivotal movement of the closure 11, but also to permit bodily movement of the closure forwardly from the boiler front 10, upon the bolts 12.

The hinge structure B' serves to support the pump A' and in turn is normally but detachably fixed to the front end closure 11 by means of the bolts and nuts 12^c, 12^d. The purpose of this arrangement of the hinge B' is to securely support the pump A' but to permit it to be swung aside from the closure 11, upon removal of the nuts from the bolts 12^c, thus clearing the path of movement of the closure 11 and associated parts such as the pump A and allow access to the interior of the boiler.

As will appear on examination of Figure 3, each of the hinge structures B, B' comprises a pair of brackets fixed to the boiler front, a movable supporting bracket of generally L-form to sustain structures disposed

in front of the boiler, and a pivotal connection between the fixed and movable brackets, the relation between the brackets of the hinge structure B being not only pivotal but 5 also sliding.

Considering first the construction, function, and operation of the hinge structure B, it will be noted that rigidly fixed to the outside surface of the boiler adjacent its 10 front end at spaced apart points are the two bracket supports, 13—13. Each of these brackets is provided with upper and lower spaced ears, 14, 14, extending forwardly from the boiler front for a substantial distance, each being provided with the elongated openings, 15, 15 in vertical registration. Passing through these openings, 15, 15 for longitudinal reciprocation therein are the pins, 16, supported from the upper ears, 20 14, by the head, 17, and retained in position against accidental loss by the cotter pins, 18. To brace these ears, 14, against distortion, each bracket support, 13, is provided with the rib member 19.

25 The front end plate 11 is mounted to swing about the pivot pins 16 as a hinge by means of the hinge member 20, extending outwardly beyond the front end plate and rigidly supported therefrom by the bracket members 21, 21, each bracket member 21 being provided with two hinge members 20. These members 20 engage around the pins 16 so as to cause the two to move together longitudinally, the pins being guided in such movement by the longitudinally extended slots 15.

By this arrangement I have provided a support for the front end plate from the boiler at two points spaced apart which will 40 permit the front end plate being moved bodily in a right line away from the boiler front, and at the same time will maintain the end plate in a position of support from the boiler.

45 There is also thus provided an arrangement whereby after the front end plate 11 has been moved bodily away from the boiler front 10 and out of engagement with the stud bolts 12, the front end plate 11 can be 50 swung bodily out of the path of the opening to the boiler front, to permit of free access to the boiler interior, while at the same time still retaining the end plate 11 in supported relation to the boiler.

55 Each of the brackets 13 is provided with the vertical rib 23 within the outlines of the boiler, from which extends the boss 24. The rib 23 and the boss 24, as well as the web portion 25, of the brace member 19 are each provided with a passage, all being in registry.

The passages through the members 23 and 24 are in registry and receive the screw-threaded portion 25^a of the actuating bolt 26 provided on its front end with the circular

portion 27, which engages the pin 16, as clearly shown in the drawing. (Figure 3.) The actuating nut 28 is carried by the bolt 26 between the web portion 25 of the flange 19 and the boss 24.

70 As a result of this arrangement, when the nut 28 is turned to move it against either the web 25, or against the boss 24, depending upon the direction in which it is turned, such member will act as an abutment for the nut 28, and the continued rotation thereof will cause the bolt 25 to travel either backwardly or forwardly. This will cause the hinge pin 16 to move in the same direction, and will, of course, carry with it the closure member 80 11.

It will be noticed that the space between the two members 24 and 25 is greater than the width of the nut 28. As a result, where 85 it is desired to move the closure toward or away from the boiler front, there will be a free space provided for the travel of the nut 28 before it reaches its abutment at either end. This is of considerable importance, as 90 it will be obvious that the nut 28, as well as the closure member 11, may stick, and the force necessary to rotate the nut would have to be sufficient to overcome not only the inertia of the door, but as well the sticking tendency of the closure member 11 and the 95 nut 28.

By providing the aforementioned full space through which the nut is moved before the closure member is acted on, the two important results are attained of having all 100 the force first applied to overcome the sticking tendency of the nut, and secondly a certain momentum is thus acquired which will make the force applied to the nut more effective in its actuation of the end plate 11. 105

The arrangement for giving the end plate 11 its bodily movement is duplicated upon each hinge, two of which are shown at points substantially spaced from one another. The action of turning first the nut upon one 110 hinge and then the other will be very similar to that used in which force is first applied at one point and then at another to pry an object loose.

Considering next the construction, function and operation of the hinge structure B, it will be observed that rigidly fixed to the outer surface of the boiler 10, and closely adjacent to its front end, I provide at spaced apart points the two bracket supports 120 13^a—13^a. Each of these brackets is provided with upper and lower spaced ears, 14^a—14^a, extending laterally from the boiler front for a substantial distance, each being provided with annular openings 15^a in vertical registration.

125 Passing through these openings 15^a are the pivot pins 16^a, each supported from the upper ear 14^a by its head 17^a, and retained in position against accidental loss by the cotter 133

pin 18^a. To brace these ears 14^a against distortion each bracket support 13^a is provided with a rib member 19^a.

The supporting structure C' is mounted to 5 swing about the pivot pin 16^a as a hinge by means of the hinge member 20^a—20^a extending laterally beyond the supporting structure C' and rigidly supported therefrom by means of the bracket members 10 21^a—21^a, each bracket member 21^a being provided with two of the hinge members 20^a. These members 20^a in both of the pivot portions encircle the pins 16^a so as to permit 15 swinging movement between the members 20^a and 14^a, limited to pivotal movement by means of the pin 16^a.

It will be observed that by virtue of the lateral displacement of the hinge members to the side of the boiler structure in each 20 instance the axes of the pivot pins 16 and 16^a are relatively widely separated from the plane in which lies the nearest of the circular row of stud bolts and nuts 12. This, in the instance of pivot pins 16 makes 25 the relative angular displacement of the front plate openings and stud bolts 12 only slight, preventing binding, and in the instance of pins 16^a, removes these latter to a point where they cannot interfere with 30 removal of adjacent stud bolts.

For additionally supporting and guiding the pins 16^a, the bracket supports 13^a are each further provided with ears 22^a positioned intermediate to ears 14^a and provided 35 with vertical openings similar to and in registry with the openings 15^a in the upper and lower ears 14^a.

As a result of the arrangement described, 40 it will be apparent to those who are skilled in the art that I am enabled to provide by means of my improved attachments and changes that may be relatively easily made in existing structures, a construction which has all of the advantages of existing structures 45 with the additional advantages due to the employment of such attachments, as hereinabove pointed out.

Reverting now to the exemplification of 50 the present invention illustrated in Figures 4 to 7, it will be observed that in most essential respects the structures here shown are quite analogous to those hereinabove described, save in certain important particulars 55 which will now be pointed out or will appear on inspection of the drawings.

The alternative form under consideration is in some ways more compact and simple in that the pumps D, D' are arranged substantially parallel to the face of the front 60 end closure 11, as is possible in certain types of locomotives where sufficient space is afforded by prevalent conditions and where such space will permit this arrangement 65 without interference with ready access to the man-hole E.

To attain this objective, the fixed brackets 13^b, 13^c are given a markedly L-form, whereby by the pivotal axes afforded by the pins 16^b, 16^c are set to the outside of the boiler, which thus permits lateral placement of the 70 pumps D, D'.

In this type of construction the hinge elements F, F' are not required to be of L-form and while the parts attached to the front end closure 11 are materially widened 75 in order to afford suitable beds for the pumps, they may be suitably skeletonized in order to save weight.

The manifold advantages of the illustrated embodiments of my present invention will 80 be readily appreciated by those who are skilled in the art to which it pertains.

Having thus disclosed my invention and illustrated its use, what I claim as new and desire to secure by Letters Patent is:

1. In combination, a boiler having an opening, a closure for said opening, a member supported in front of and in part only by said closure, and means whereby said member may be moved away from said closure to permit said closure to be moved.

2. In combination, a boiler having an opening, a closure for said opening, a member supported in front of and in part only by said closure, and pivoted means whereby said member may be moved laterally to permit said closure to be moved.

3. In combination, a boiler having an opening, a closure for said opening, pivotally supported in position, a member supported in front of said closure spaced from the pivot thereof, and means whereby said member may be moved to permit said closure to be moved.

4. In combination, a boiler having an opening, a closure for said opening, pivotally supported in position, a member supported in front of and in part only by said closure, and pivoted means whereby said member may be moved to permit said closure to be moved.

5. In combination, a boiler having an opening, a closure for said opening, pivotally supported in position, a member supported in front of said closure, and means whereby said member may be moved laterally in one direction to permit said closure to be moved laterally about its pivot in another direction.

6. In combination, a boiler having an opening, a closure for said opening, pivotally supported in position, a member supported in front of said closure, and means whereby said member may be moved laterally in one direction to permit said closure to be moved bodily about its pivot forward and laterally in another direction.

7. In combination, a boiler having an opening, a closure for said opening, slidably and pivotally supported in position, a mem-

- ber supported in front of said closure, and means whereby said member may be moved laterally in one direction to permit said closure to be moved bodily forward and laterally in another direction. 5
8. In combination, a boiler having an opening, a closure for said opening, means for supporting said closure for sliding movement, cooperating means for supporting said closure for pivotal movement arranged adjacent to one side of the boiler, a member in front of said closure, and means for supporting said member for pivotal movement arranged adjacent to the opposite side of the boiler. 15
9. In combination, a boiler having an opening, a closure for said opening, means for supporting said closure for pivotal movement arranged adjacent to one side of the boiler, a member detachably supported by said closure, and means for supporting said member for pivotal movement arranged adjacent to the opposite side of the boiler. 20
10. In combination, a boiler having an opening, a closure for said opening, means for supporting said closure for sliding movement, cooperating means for supporting said closure for pivotal movement arranged adjacent to one side of the boiler, a member detachably supported by and in front of said closure, and means for supporting said member for pivotal movement arranged adjacent to the opposite side of the boiler. 25
11. In combination, a boiler having an opening, a closure for said opening, a member supported in front of said closure, and a hinge structure for said closure serving as a bed for said member. 30
12. In combination, a boiler having an opening, a closure for said opening, a member supported in front of said closure, and a hinge structure for said closure having a forwardly projecting part serving as a bed for said member. 35
13. In combination, a boiler having an opening, a closure for said opening, a member supported in front of said closure, and a hinge structure for said closure having a generally L-form, one face thereof being attached to said closure and another face thereof serving as a bed for said member. 40
14. In combination, a boiler having an opening, a closure for said opening, a member supported in front of said closure, and a hinge structure for said closure serving as a bed for said member, said hinge structure being adapted to permit both bodily and pivotal movement of said closure relatively to the boiler. 45
15. In combination, a boiler having an opening, a closure for said opening, a member supported in front of said closure, and a hinge structure for said closure having a forwardly projecting part serving as a bed for said member, said hinge structure being 50
- adapted to permit both bodily and pivotal movement of said closure relatively to the boiler. 55
16. In combination, a boiler having an opening, a closure for said opening, a member supported in front of said closure, and a hinge structure for said closure having a generally L-form, one face thereof being attached to said closure and another face thereof serving as a bed for said member, 60 said hinge structure being adapted to permit both bodily and pivotal movement of said closure relatively to the boiler. 70
17. In combination, a boiler having an opening, a closure for said opening, a plurality of members supported in front of said closure, and a pair of hinge structures arranged on opposite sides of the boiler, one hinge structure serving as a support for said closure and one of said members and the other hinge structure serving as a support for another of said members. 80
18. In combination, a boiler having an opening, a closure for said opening, a plurality of members supported in front of said closure, and a pair of hinge structures arranged on opposite sides of the boiler, each having a forwardly projecting part, one hinge structure serving as a support for said closure and one of said members and the other hinge structure serving as a support for another of said members, the said members sustained by said forwardly projecting parts. 85
19. In combination, a boiler having an opening, a closure for said opening, a plurality of members supported in front of said closure, and a pair of hinge structures of generally L-form arranged on opposite sides of the boiler, one hinge structure serving as a support for said closure and one of said members and the other hinge structure serving as a support for another of said members. 90
20. In combination, a boiler having an opening, a closure for said opening, a plurality of members supported in front of said closure, and a pair of hinge structures arranged on opposite sides of the boiler, one hinge structure serving as a support for said closure and one of said members and the other hinge structure serving as a support for another of said members, the first mentioned hinge structure being adapted to permit both bodily and pivotal movement of said closure relatively to the boiler. 95
21. In combination, a boiler having an opening, a closure for said opening, a plurality of members supported in front of said closure, and a pair of hinge structures arranged on opposite sides of the boiler, one hinge structure serving as a support for said closure and one of said members and the other hinge structure serving as a support for another of said members, and said last 100
- 110
- 115
- 120
- 125
- 130

mentioned hinge structure being detachably secured to and supported by said closure.

22. In combination, a boiler having an opening, a closure for said opening, a plurality of members supported in front of said closure, and a pair of hinge structures arranged on opposite sides of the boiler, each having a forwardly projecting part, one hinge structure serving as a support for said closure and one of said members and the other hinge structure serving as a support for another of said members, the said members sustained by said forwardly projecting parts, and said last mentioned hinge structure being detachably secured to and supported by said closure.

23. In combination, a boiler having an opening, a closure for said opening, a plurality of members supported in front of said closure, and a pair of hinge structures of generally L-form arranged on opposite sides of the boiler, one hinge structure serving as a support for said closure and one of said members and the other hinge structure serving as a support for another of said members, and said last mentioned hinge structure being detachably secured to and supported by said closure.

24. In combination, a boiler having an opening, a closure for said opening, a plurality of members supported in front of said closure, and a pair of hinge structures arranged on opposite sides of the boiler, one hinge structure serving as a support for said closure and one of said members and the other hinge structure serving as a support for another of said members, and said last mentioned hinge structure being detachably secured to and supported by said closure.

25. In combination, a boiler having an opening, a closure for said opening, a plurality of members supported in front of said closure, and a pair of hinge structures arranged on opposite sides of the boiler, one hinge structure serving as a support for said closure and one of said members and the other hinge structure serving as a support for another of said members, and said last mentioned hinge structure being detachably secured to and supported by said closure.

26. In a device of the character described,

in combination, a container having an opening, a closure for said opening, means for pivotally mounting said closure at one side of said opening, an auxiliary supporting structure carried by said closure adjacent said means and movable with the closure, and an additional supporting structure pivotally mounted on the container at the opposite side thereof.

27. In a device of the character described, in combination, a container having an opening, a closure for said opening, means for pivotally mounting said closure at one side of said opening, an auxiliary supporting structure carried by said closure adjacent said means and movable with the closure, an additional supporting structure pivotally mounted on the container at the opposite side thereof, and means for fixing the last named supporting structure to said closure.

28. In a device of the character described, in combination, a container having an opening, a closure for said opening, means for pivotally and slidably mounting said closure at one side of said opening, an auxiliary supporting structure carried by said closure adjacent said means and movable with the closure, and an additional supporting structure pivotally mounted on the container at the opposite side thereof.

29. In a locomotive boiler having an opening, in combination, a closure plate for said opening, a supporting structure adjacent to one side of said closure plate, a hinge for pivotally supporting the closure plate on the boiler, said supporting structure being mounted on the boiler to swing out of the path of said closure plate when the latter is moved about its pivot.

30. In a locomotive boiler having an opening, in combination, a closure plate for said opening, a plurality of supporting structures within the outlines of the boiler adjacent to opposite sides thereof and to said closure plate, a hinge for pivotally supporting the closure plate on the boiler, one of said supporting structures being mounted on the boiler to swing laterally out of the path of said closure plate when the latter is moved about its pivot.

In testimony whereof, I have hereunto signed my name.

HARRY VISSERING.
